UNITED STATES PATENT OFFICE.

STEPHEN E. BRADY, OF GRANBY, MISSOURI, ASSIGNOR OF ONE-HALF TO CHARLES A HINES AND LINCOLN HINES, OF ANDERSON, MISSOURI.

SPLICE-BAR.

1,088,058.

Specification of Letters Patent.

Patented Feb. 24, 1914.

Application filed June 10, 1913. Serial No. 772,822.

To all whom it may concern:

Be it known that I, STEPHEN E. BRADY, a citizen of the United States, residing at Granby, in the county of Newton and State 5 of Missouri, have invented new and useful Improvements in Splice-Bars, of which the following is a specification.

This invention relates to improvements in splice bars for connecting the meeting ends 10 of two railway rails, and resides in the construction, combination and arrangement of parts set forth in the following specification and falling within the scope of the appended claim.

15 In the drawing there has been illustrated a simple and preferred embodiment of the improvement reduced to practice, and in which drawing:

Figure 1 is a perspective view of a rail 20 joint constructed in accordance with the present invention, Fig. 2 is a central longitudinal sectional view through the same, Fig. 3 is a transverse sectional view on the line 3—3 of Fig. 2, Fig. 4 is a sectional view 25 on the line 4—4 of Fig. 2, Fig. 5 is a perspective view of one of the splice bars or joint plates, and Fig. 6 is a similar view of the co-acting splice bar or joint plate.

Referring now to the drawing in detail, 30 R—R designate two railway rails, which are of the ordinary construction, and which have their webs adjacent their ends formed with the usual bolt openings.

The splice bars which form the joint of 35 the ends of the rails are designated by the numerals 1 and 2 respectively, the bar 1 being adapted to be arranged upon the outer side of the rails, and the bar 2 adapted to be arranged upon the inner sides of the rails.

40 The splice bar 1 comprises a member which is formed with an enlarged central portion or body 3, the upper face of the body being inclined or curved from its upper edge to its lower longitudinal edge, and the said

45 body has its underface provided with a longitudinally extending bevel or channel 4 which is inclined to agree with the base flanges of the rails upon which the same is adapted to rest, and the body at the junction of the channel is formed with a vertically straight longitudinal ledge or wall 5 which is adapted to abut against the outer

50 longitudinal edges of the rails R—R. The upper portion of the body has its inner edge beveled, as at 6, to agree with the underfaces

of the heads of the rails with which it is adapted to engage. The inner face of the portion of the body which engages with the webs of the rails is formed with a plurality of sockets or depressions corresponding in 60 number with the bolt openings in the webs of the rails, and adapted to be arranged to align with the said bolt openings when the splice bar 1 is arranged upon the rails. The ends of the splice bars are reduced extensions 7 and 8, each of the said extensions being provided with an opening 9 and the said openings are adapted to register with the innermost bolt openings in the webs of 65 the rail.

70 The splice bar 2 is of a shape substantially similar to that of the splice bar 1, it being formed upon its lower face with the inclined channel 10 which engages with the base flanges of the rail, and with the projecting portion 11 which engages within the fishing spaces of the rails. The upper edge 75 of the splice bar 1 directly opposite the inner inclined shoulder 12 upon which the underfaces of the rail heads rest, is provided 80 with a longitudinally extending depression or channel 13 for the reception of the flanges of the wheels of the rolling stock passing over the joint, and to provide the plate 2 with a rail guard 14. The body is formed 85 with extensions 15, similar to the end extensions upon the splice bar 1, and these extensions are formed with openings which are adapted to register with the openings in 90 the extensions of the splice bar 1, and the registering openings are adapted to receive securing bolts which are provided with retaining nuts. The splice bar 2 is formed 95 with a plurality of transversely arranged projecting fingers 16 which project through the bolt openings in the webs of the rails into the depressions in the opposite splice bar.

100 From the above description, taken in connection with the accompanying drawing, the simplicity of the device as well as the advantages thereof will, it is thought, be perfectly apparent to those skilled in the art to which such inventions appertain without further detailed description.

105 Having thus described the invention, what I claim is:

The combination with two rails having abutting ends, of splice bars for the opposite sides of the rail ends, each of said bars in- 110

cluding an enlarged laterally extending body having inclined sides and provided with reduced extending ends, the inner portions of the bodies and extending ends of which are received within the fishing spaces of the rails, one of said enlarged bodies being integrally formed with spaced fingers which pass through bolt openings in the webs of the rails and are received within depressions provided in the inner face of the second splice member, the longitudinally extending ends of the splice members having lateral openings which register with openings in

the webs of the rails, bolts passing through the openings, nuts for the bolts, and one of 15 said splice members having its beveled side recessed longitudinally, the inner wall of the said recess being arranged flush with the outer face of the end extensions of the said splice member. 20

In testimony whereof I affix my signature in presence of two witnesses.

STEPHEN E. BRADY.
